LIQUID SEPARATING APPARATUS

George A. Auer, Chicago, Ill.

Application August 6, 1945, Serial No. 609,070

3 Claims. (Cl. 209—157)

1

This invention is concerned with a hydraulic streamcurrent apparatus for separating materials.

The term—streamcurrent—has been defined in Patents Nos. 2,386,419, 2,391,858 and 2,464,418. It refers to the control of a fluid or liquid body in motion for the purpose of producing rational hydraulically substantially stable agitation in the presence of which solid and fluid particles will exhibit a predictable behavior, as distinguished from unpredictable behavior of particles in a liquid or fluid medium which is agitated in a manner that produces irrational turbulence.

Irrational turbulence is produced, e. g., by the operation, in a fluid mass, of mechanical elements, rotating paddles, stirrer arms and the like, whether they are driven directly or by hydraulic reaction. Such turbulence is characterized by meandering vortices and eddies, dead pockets, migrating variable fields of stagnation. It is un-uniform, unpredictable, not subject to rational analysis. The separation of solid particles in and from such irrationally agitated turbulent mass, as heretofore practiced, is likewise un-uniform, unpredictable, therefore irrational.

Rational agitation is produced by streamcurrent control of a fluid medium as broadly defined above. Applied to the hydraulic separation of materials, the term specifically means a rational hydraulic displacement of the body of a fluid separating medium which proceeds upwardly and laterally symmetrically outwardly with upwardly diminishing magnitude or upward velocity, and substantially without creating irrational turbulence therein.

The above noted co-pending patents may be consulted for antecedents, general principles and theoretical considerations which apply in the present case especially with regard to observations relating to the prior art and to the behavior of solids in liquids.

Some of the principal objects and features of the present invention may be briefly summarized as follows:

One object is to provide a separator equipped with feed means for supplying the raw material in adjustable, measured, uniform amounts, which are released either intermittently or consecutively in adjustable measured increments forming a steady uniform stream.

Another object is to provide a turbulence chamber containing a normally quiescent body of liquid for receiving the raw material from the feed means intimated in the preceding paragraph and for subjecting the raw material in such liquid

2

body to irrational turbulence for the purpose of wetting the particles, breaking up agglomerates, preventing packing, and generally for the purpose of thoroughly dispersing the particles in and intermixing them with the liquid.

A further object is to provide a separator having a separating chamber equipped with means for supplying liquid to its base, means for supplying liquid in upwardly decreasing amounts centrally axially of the chamber, and a plurality of serially related flow control members forming a generally vertically extending flow-distributing wall forming a series of vertically spaced, peripherally or circumferentially unobstructed outlets or discharge ports which permit selective withdrawal of liquid in upwardly increasing amounts from corresponding vertically spaced levels of the liquid body in the chamber.

Still another object is to provide means forming settling chambers which communicate hydraulically with the body of liquid in the streamcurrent chamber at vertically spaced levels thereof, and means for selectively withdrawing adjustable amounts of liquid from said settling chambers and returning such withdrawn liquid to the inlet means for the purpose of creating in the separating chamber the streamcurrent displacement of the fluid body contained therein which proceeds upwardly and laterally outwardly, with upwardly diminishing magnitude or upwardly diminishing upward velocity, and substantially without creating irrational turbulence therein.

The turbulently agitated, wetted and highly mobile raw material particles are discharged from the turbulence chamber downwardly in a steady stream directly and immediately into the path of the upwardly directed streamcurrent flow, axially centrally thereof, and the particles can now orient themselves rationally in accordance with their specific gravities. The lightest particles move laterally directly for discharge at the top of the separating chamber, progressively heavier particles move downwardly and laterally outwardly for discharge through outlet ports disposed at vertically downwardly successive levels of the liquid body in the separating chamber, and the heaviest particles gravitate downwardly to a bottom discharge port where they are withdrawn. There is no lost motion and no confusion. The separation is direct and begins instantly at the moment the particles enter the liquid separating medium which is subjected to the streamcurrent displacement.

55 The invention also provides bleeder means

extending from the turbulence chamber into the streamcurrent separating chamber for the purpose of draining fluid containing accumulated fines downwardly to avoid undesirable increase of the density of the liquid in the turbulence chamber.

Other objects relate to the provision of a secondary streamcurrent separator or sump for receiving the underflow from de-watering screens and for separating from such underflow valuable fines, refuse fines, and returning residual liquid to the primary streamcurrent separator.

These and additional objects and features are described below in detail with reference to the accompanying drawings, wherein

Fig. 1 illustrates in a schematic manner a vertical cross-section through an embodiment of a primary streamcurrent separator made in accordance with the invention;

Fig. 2 is a flow diagram showing essential equipment in a system comprising a primary streamcurrent separator as illustrated in Fig. 1, and also showing a secondary streamcurrent separator or sump; and

Fig. 3 represents a partial sectional view of the separator or sump shown in Fig. 2.

The drawings are diagrammatic and not to scale; they are intended for illustrative and descriptive purposes only. Like parts are indicated by like reference numerals. Known elements will be referred to only to the extent required for an understanding of the invention.

Referring now to Fig. 1, the primary streamcurrent separator comprises a vertically disposed tank having an upper cylindrical section 11 and a lower inverted conical section 12. Inside of section 12 are provided inserts or baffles 13-17. These baffles, in the embodiment shown, are circular and each extends substantially in parallel with the outer tank wall. Each baffle may be supported in its position by suitable brackets which are not shown in the drawing. Upwardly successive inserts or baffles recede radially outwardly toward the outer tank wall. In other words, the baffle 13 is spaced widest from the tank wall 12; the baffles 14-16 are progressively closer to the tank wall 12; and the downwardly and inwardly directed lower end of baffle 17 is closest to the tank wall. The top edge of baffle 13 accordingly overlaps the bottom edge of the baffle 14; the top edge of baffle 14 overlaps the bottom edge of baffle 15; the top edge of baffle 15 overlaps the bottom edge of baffle 16; and the top edge of baffle 16 overlaps the bottom edge of baffle 17. This overlapping relationship of the baffles minimizes and substantially prevents the occurrence of undesired irrational turbulence of uprising currents peripherally within the separating chamber.

The baffles 13-17 are vertically spaced as shown in the drawing, to provide peripherally or circumferentially unobstructed ports or openings 18-21 for the symmetric withdrawal or discharge of material from the separating chamber. An insert 22 is provided in back of the bottom baffle 13. This insert is inclined at an angle to the vertical axis of the separator and forms a spillway which receives the material discharged through the outlet port 21. Similar inserts 23-25 are provided in connection with the baffles 14-16, respectively, forming inclined spillways for receiving the material discharged through the ports 20-19-18, respectively. The insert 13 forms with the tank wall 12 an inlet chamber 26, and the inserts 14-17 form with the outer tank wall

12 settling and discharge chambers 27-30. The upper end of the insert 17 extends in parallel with the cylindrical section 11 of the tank and forms the settling chamber 30 therewith.

5 The material discharged through the outlet ports 21-20-19-18, respectively, flows into the chambers 27-28-29-30, respectively, and may be drawn off from the bottom of these chambers through the valve controlled outlets 31-34, respectively. These outlets are schematically shown in the form of pipes. They may receive different form, e. g., the form of conduits terminating in conveyer or elevator casings, and slide valves of the type diagrammatically shown in Fig. 2 at 103, 15 in connection with the refuse discharge 102 may be used for regulating the flow of material from the outlets.

The inlet chamber 26 underneath the spillway 22, which spaces the baffle 13 from the tank wall 12, is connected with an inlet controlled by the valve 35. Circular rows of slots, as indicated at 36, are provided at the bottom of the baffle 13 for diffusing liquid injected into the chamber 26 through the inlet controlled by valve 35. These rows of slots may be replaced by an open port such as ports 21-20-19-18, and the latter in turn may be replaced by slots as shown at 36. Either structure provides a peripherally or circumferentially unobstructed communication with the liquid body in the separating chamber.

30 Arranged in parallel with the inlet controlled by valve 35 is an inlet controlled by the valve 37, and both in turn are connected with valve 38 which is part of the conduit coming from the pressure side of the pump 39. The inlet controlled by valve 37 is connected with a pipe 40 extending upward centrally axially of the separating chamber, as shown. The pipe 40 is provided with a series of vertically spaced outlets of upwardly progressively diminishing size. Therefore, liquid injected through the valve 37 enters the interior of the structure in upwardly decreasing amounts, as generally indicated by the relative prominence of the flow lines. The openings in the pipe 40 may be circumferentially contiguous slots, as shown, e. g., at 26. The inlet pipe may be a structure assembled of pipe sections joined by tubular peripherally perforated sections forming outlet ports at each level where liquid is to be injected. Outlets which may be formed in a top closure operating as a spray-head are also provided at the upper end of pipe 40.

45 Liquid injected through the valve 35 into the inlet chamber 26 and through valve 37 into the inlet pipe 40 diffuses through the slots 36 and through the ports in the pipe 40 and floods the interior of the separating chamber, moving upwardly and laterally outwardly with upwardly diminishing magnitude and velocity, as generally indicated by the relative prominence of the flow lines.

50 The discharge chambers 27-30 extend upwardly from the associated discharge conduits. They may be of considerable size, depending upon the ton-hour capacity of the separator, and function as settling chambers. The capacity of these chambers may be increased by making the outer tank cylindrical, as disclosed in the prior Patent No. 2,386,419 and Patent No. 2,464,418. The 55 chambers are flooded by liquid from the separating chamber and solids settle therein for removal through the discharge conduits, leaving clarified liquid on top. Valve controlled pipes 27a, 28a, 29a, 30a connect the corresponding settling chambers with the conduit 11, which feeds liquid to the

pump 39 by way of the pipe 15. Adjusted amounts of liquid can thus be withdrawn from the settling chambers, that is, from the various levels of the liquid body in the separating chamber and symmetrically peripherally thereof. Suction pipes such as shown at 10 and 13 may be provided in the settling chambers.

The flow of liquid within the separating chamber is thus controlled by the flow-distributing wall formed by the inserts or baffles 13-17; by the manner of injecting liquid at the bottom through the inlet chamber 26 and the pipe 40, respectively; and by the amounts of liquid withdrawn in a controlled manner through the valve controlled outlets 28a-30a. The resulting displacement of the liquid body within the separating chamber is the streamcurrent displacement previously referred to.

The tank may be provided with a lid or cover 45. The cover forms centrally thereof a circular downwardly and inwardly depending flange 46. A tubular open-ended feed conduit having an inverted conical portion 47 and an upper cylindrical portion 48 is provided with brackets 49-50 which support it centrally of the cover 45, the inverted conical portion 47 depending downwardly centrally axially into the streamcurrent separating chamber. The flange 46 depending from the cover also supports the conduit 47 and centers it in proper position with respect to the streamcurrent chamber. The open-ended bottom of the feed conduit is disposed somewhat below the top discharge port 18.

A hood 51 extends upwardly from the cylindrical portion 48 of the feed conduit and is provided with a chute 52 which connects with the discharge end of a hopper 53.

At the lower end of the feed conduit 47 is provided a bearing 54, carried by a suitable bracket, for journaling the lower end of a shaft 55 which is journalled at its upper end in a bearing 56. A suitable driving mechanism, which may include bevel gears 57-58, is provided for rotating the shaft 55. The shaft also carries stirrer arms or paddles 59-63.

The structure including the tubular feed conduit 47, with its shaft and stirrer arms, constitutes a feed passage for the raw material and the turbulence chamber of the separator. The raw material drops from the hopper 53 through the chute 52 into the liquid contained in the feed conduit 47 and is subjected therein to irrational turbulence by the operation of the paddles or stirrer arms attached to the shaft 55.

Secured to the tank cover 45 and depending therefrom is a peripheral baffle or insert 65 forming a peripheral top settling chamber 66. Another insert or baffle 67 is secured to the cover 45 centrally thereof, forming with the wall of the auxiliary tank 47 an annular axially extending settling chamber 68. Liquid drawn into these chambers through the inlets at the bottom of the inserts 65 and 67 is subjected to quiescent conditions, and solid material can therefore settle downwardly in these chambers. Near and at the top of these chambers there will be substantially clear liquid.

Disposed in the upper strata of the settling chamber 66 is a circular pipe 70 connected with the conduit 71 by way of the valve 72. A pipe 73 is similarly disposed in the settling chamber 68 which connects with the conduit 71 by way of the valve 74. Clear liquid withdrawn from the settling chambers 66 and 68 can thus be pumped back and can be injected by way of

valves 35 and 37 into the inlet chamber 26 and into the centrally disposed inlet pipe 40. The two settling chambers 66 and 68 form additional means for controlling the streamcurrent displacement in the separating chamber by withdrawal of liquid therefrom and reinjection of the liquid through the inlet means.

The mechanism for controlling the feeding of the raw material from the hopper 53 into the apparatus constitutes an improvement on the structure disclosed in U. S. Patent No. 2,334,337. It comprises a shield 80 which extends transversely across the hopper, being rotatably mounted at 81 on a shaft which is journalled in the side walls of the hopper. This shield can thus be placed into the dotted line position, as shown in Fig. 1, or into the cross-hatched central position, or into a position opposite from that shown in dotted lines. Chute baffles 82-83 are disposed within the hopper, as shown, for directing the raw material downwardly and laterally inwardly against the shield 80. When the shield 80 is disposed in the central cross-hatched position, material flows downwardly on either side thereof. When the shield is tilted to the left, into the dotted line position, material flows downwardly only on the right side thereof, through the opening between the shield and the baffle 83; and when the shield is tilted to the right into a position opposite to that in which it is shown in dotted lines, material flows downwardly only on the left side through the space between the shield and the baffle 82. The shield 80 functions in this manner in the nature of a valve for directing the raw material downwardly along one or the other or along both of its side walls.

Below the shield 80 and spaced therefrom is disposed a tray having two tray members 85 and 86 which extend transversely across the hopper, just as the shield 80, in a plane perpendicular to the plane of the drawing Fig. 1. The tray members are separated by a central opening 87, as shown. This tray with its two members 85-86 is mounted on opposite sides of the hopper by flanges such as 88.

An arcuate scraper having two segment-shaped mounting members 89 is pivotally mounted on a shaft 90 disposed just below the pivot point 81 of the shield 80. Stub shafts may be used, one with each of the segment-shaped end plates 89. The scraper is provided with two scraper members 91-92 depending downwardly in close proximity to the upper surface of the tray members 85-86. The shaft 90 of the scraper extends outside of the hopper housing 53 in back of the side wall thereof, as shown in Fig. 1, and attached to the shaft is a rocker arm shown in dotted lines and indicated by the numeral 93. This rocker arm coacts with a connecting rod 96 which extends from an eccentric 97 operable by a shaft 98. It will thus be clear that rotation of the shaft 98 causes rotation of the eccentric 97 and reciprocation of the connecting rod 96, with consequent rocking motion of the lever or arm 93 and rocking motion of the scrapers 91-92 with respect to the tray members 85-86.

The tray and its members 85-86, and also the tray-like member carrying the scrapers 91-92, are so shaped and dimensioned that raw material dropped downwardly normally assumes an angle of repose which inhibits the free downward flow thereof. If the shield 80 is disposed centrally, as shown in cross-section, material flows downwardly on either side thereof and piles up on the tray members 85-86. Reciprocation

of the scraper by the arm 95, responsive to rotation of the eccentric 97, results in ejection of consecutive increments of material alternately from the left and right of the tray members 85—86. The stroke with which the arm 95 is reciprocated may be regulated by placing the lower end of the connecting rod 96 adjustable at various points along the arm 95. For this purpose the arm 95 may be provided with a series of holes for variably attaching the connecting rod 96.

It will be seen from the above description of the feeding device that raw material may be fed from the hopper downwardly into the separator in adjustable measured amounts, either intermittently or in a steady stream composed of consecutively released measured increments of material. The amounts or increments released in either case are adjustable by the stroke of the rocker arm 95 and the frequency of release of material is adjustable by the speed of operation of the eccentric 97. The feed mechanism prevents erratic and haphazard supply of raw material to the separator, thereby preventing overloading or underfeeding of the liquid separating medium. The optimum feed can be easily determined for any given raw material which is to be subjected to separation.

The operation of the separator may be described with reference to both Figs. 1 and 2. For the sake of convenience, it will be assumed that the raw material is coal within a size range from about $\frac{1}{4}$ " to 0".

The machine is first filled with water which is obtained from the makeup water conduit 100, being pumped into the separator by the pump 39 through the valves 38, 35 and 37. Valves 72 and 74, and also the valves in the pipes 27a, 28a, 29a and 30a, are closed during the initial filling operation. The valve 101 (Fig. 2) in the return water line from the sump is likewise closed. Suitable vent valves may be provided wherever desired or necessary so as to allow the escape of air from the various chambers. A level gage may likewise be provided as desired. Water rises within the separator up to a predetermined level near the cover of the machine. If desired, a float may be provided for controlling the initial filling operation and for automatically maintaining a constant level in the separator during the operation thereof. It is, of course, understood that the cover may be dispensed with and suitable means may be provided for supporting the various baffles and inserts and also the feed conduit 47. The upper cylindrical portion 11 of the separator tank may for this purpose be extended upwardly as may be necessary. It should be observed that water also rises within the feed conduit 47, providing the normally quiescent body of liquid for receiving the stream of raw material.

The drive mechanism, including the gears 57—58, may then be started to rotate the paddles 59—63 to provide turbulence within the feed conduit 47. Streamcurrent circulation is started in the separating chamber by opening the valves 72 and 74 and the valves in the pipes 27a—30a to circulate water from the various settling chambers downwardly for reinjection through the inlet chamber 26 and the centrally axially extending pipe 40. Upward streamcurrent displacement of the body of water within the separating chamber in accordance with the flow lines upwardly and laterally outwardly is thus initiated.

The magnitude of the streamcurrent displacement is, of course, different for any given raw material and is adjusted in accordance with the specific gravity of the particles and/or particle sizes which it is desired to save and to reject, respectively. For example, the upward terminal velocity of the streamcurrent flow at the top discharge level 18 must be different in case of coal of 1.35 specific gravity and a size range from $\frac{1}{4}$ " to 0" than in case of heavier coal within a different size range. Material containing a great amount of fines may require different treatment than material which is relatively free of fines. In the latter case, which is assumed in the drawings, it may be decided to discharge the lightest components at the top port 18 through the discharge conduit 34, and in the former case, it may be preferable to remove only or mainly the fines at the top level and to discharge relatively fine-free lightest particles through the port 19 and discharge conduit 33. These examples are given for convenience of description and do not indicate any inherent limitations as to the precise procedure which may be called for in any actual operation. The structure presents many operating possibilities for creating practically any desired uprising current condition.

The streamcurrent flow which is adjusted must also be correlated with the amount of material fed into the machine for separation therein, and with the amounts of material, separated products as well as water, which are withdrawn in operation from the bottoms of the various discharge and settling chambers 27—30. It is, of course, possible to leave the proper valve settings to the operator in the field, as it is being done with previously known separators, who simply starts the machine as described and then starts feeding raw material thereto, samples the various discharged products, and makes corrections, as may be required, by setting the various valves and adjusting the raw material feed so as to obtain the desired separation.

The present invention furnishes the possibility of calibrating the various adjustments, raw material feed, speed of rotation of the shaft and paddles in the turbulence chamber formed by the feed conduit, and settings of the various valves, in accordance with the needs of any given raw material. This is done by operating the machine through a number of test runs, under supervision of the factory, using materials whose analysis is known, and calibrating index means provided with such adjustments in terms of particle size and/or specific gravities. Water meters may be used for such calibrating or pre-adjustment in connection with the various valves so as to permit calculation of the upward displacement within the separator from the amounts of liquid which is displaced at each level of the liquid body. With such calibration, the operator in the field merely has to know the analysis of the raw material which he wants to treat and sets the adjustments accordingly, as specified by the factory.

The separator being filled with water, and streamcurrent displacement as well as turbulence in the turbulence chamber being in operation, as previously described, the machine is now ready to receive the stream of raw material particles, which is also adjusted to an optimum, and to perform the pre-treatment in the feed conduit and the separation in the separating chamber.

The raw material is fed into the hopper 53 by

a suitable feeder, and rotation is imparted to the shaft 98, at a desired speed, so as to actuate the eccentric 97 for the purpose of reciprocating the scrapers 91 and 92. Assuming that the feed device is in the position shown in Fig. 1, we will have a continuous flow of material downwardly through the funnel 52 into the machine. The amount of material thus supplied in a continuous regulated stream may be variable from a minimum to a maximum by adjustment of the connecting rod 96 with respect to the rocking lever 95 and adjustment of the speed of the eccentric 97. The material drops down into the turbulence chamber formed by the feed conduit 47 and is subjected therein to irrational turbulence provided by the rotating paddles 59—63.

The purpose of subjecting the material to irrational agitation will be clear from what has been said before. Agglomerates are broken up and the raw material particles are distributed or dispersed in the liquid body within the feed conduit. It should be observed that the paddles 59—63 are successively tilted in alternate directions. The purpose is to provide for maximum agitation by imparting to the mass in the feed conduit not only a rotary beating and churning force but also alternate zones in which the mass receives upward and downward thrusts, respectively. Stationary baffles projecting from the inner wall of the feed conduit may be provided, if desired, to aid in imparting turbulence and to break the rotary motion of the turbulent mass which it otherwise would assume. Rotary motion imparted to the mass by the bottom paddles 63 is broken by the stationary bracket which secures the bearing 54. Any practically desired degree of turbulence may thus be produced.

The agitation and the turbulence produced within the feed conduit is wholly irrational, in the sense explained before. It furnishes the desired dispersion of the raw material in the liquid and imparts to the particles the mobility which is required for motion through the liquid separating medium. The wetting of the particles is believed to be important because occluded air or a surface film of gas surrounding a particle changes its apparent specific gravity in the separating medium and creates confused conditions. The air is removed in the present case and the particles are wetted, that is, they are surrounded by a film of liquid of the dispersion medium and therefore offer no resistance to movement through the separating liquid. They are mechanically mobile and therefore respond instantly to the streamcurrent flow upon ejection from the turbulence chamber downwardly directly into the path of the streamcurrent flow in the separating chamber. It should be observed that the particles do not plunge into the liquid in the streamcurrent chamber but are eased into it from above. The irrational mixing and wetting operation may require a considerable degree of irrational turbulence which under orthodox operations would make separation quite impossible. In the present case, the irrational turbulence accomplishes its purpose without affecting rational separation.

The lightest particles, or fines, depending upon conditions previously mentioned, travel directly upwardly and laterally outwardly with the similarly directed currents in the streamcurrent chamber; the heavier particles move directly downwardly through the upwardly directed streamcurrent flow and successively laterally outwardly to the respective outflow discharge levels

in accordance with their specific gravities; and the heaviest particles move directly downwardly for discharge through the discharge neck 102 which may be provided with a slide valve 103.

It will be seen from the foregoing that we have in the present case settling of the particles without any interference by mechanical elements or by irrational turbulence or cross-currents, in a liquid body which is rationally upwardly displaced in a streamcurrent flow as defined before. The particles can therefore actually settle in accordance with well known laws. It is believed that this is the first instance of an industrial uprising current separator which is capable of accomplishing this result.

The heaviest components of the raw material which move into the discharge neck or spout 102 are taken up by a suitable encased elevator or conveyer of known structure and are moved to the de-watering screen 104 shown in Fig. 2. The elevator may be of the bucket type enclosed in a suitable housing and rising from the discharge neck 102 in a manner well known in the art. In the case of coal the heaviest particles are, of course, refuse, and the flow of the refuse is indicated in Fig. 2 in dash lines. The material discharged through the conduits 31—33 may also be refuse and may be joined with the material flowing to the refuse de-watering screen 104. The conduits 31—33 may likewise terminate in elevator casings similar to the one which removes the refuse from the discharge neck 102. One of the products, for example, that removed through the conduit 33, may contain valuable material and in that case it may be recirculated as middlings through the dot-dash line conduit 105 for re-injection into the separator. The clean coal is drawn off by means of a similar encased conveyer or elevator device, and takes the dotted course shown in Fig. 2 to the de-watering screen 110.

The separated products are removed, with a minimum of water, from the bottoms of the respective discharge and settling chambers, while clear water is recirculated from such chambers to maintain the streamcurrent flow. The arrangement contributes to the economy of operation.

The de-watering screens discharge the underflow downwardly through the conduits 111 into the inflow control tank 112. This tank may be provided with a suitable device, e. g., a simple float valve, indicated in dotted lines, which regulates the flow down into the sump by maintaining a substantially constant level. The float, if centrally disposed, as indicated in Fig. 2, may be protected by an umbrella-like shield which deflects the flow of liquid downwardly and radially outwardly around the float bulb.

The sump labeled in Fig. 2 as "S.C.Sump," meaning streamcurrent sump, is, of course, a separator taking care of separating the valuable fines, which may be contained in the underflow from the de-watering screens, from the refuse, and also for recovering water which is returned to the primary streamcurrent separator. The sump may be of the same general structure as the streamcurrent separator shown in Fig. 1, or, for example, of the same general structures as the machines disclosed in Patent No. 2,386,419 and Patent No. 2,464,418, with certain improvements which are illustrated in Fig. 3.

Referring now to Figs. 2 and 3, the inflow pipe 113 coming from the constant level sump inflow control tank 112 terminates near the bottom of the structure and the underflow mass is

discharged downwardly onto the deflector 114, which is vertically adjustable by means of an adjusting member, e. g., a hand-wheel 115, or its equivalent. The flow-deflecting member 114 directs the current incoming from the inflow pipe upwardly and laterally outwardly and protects the discharge ports 120 against undesired turbulence which might otherwise occur at the bottom of the separating chamber. The heaviest particles go over the edge of the deflector 114 and gravitate without interference downwardly for withdrawal through the ports 120. Numeral 116 is a stationary water-tight bushing through which projects the threaded shaft of the baffle 114. The flow coming from the sump inflow control device 112, and therefore the stream-current flow within the separating chamber, may thus be regulated. Assuming that the separator used for the sump is of the streamcurrent type similar to the one shown in Fig. 1, we have again a number of upwardly extending baffles or insert members, as indicated at 117 and 118 in Fig. 3, which are arranged in staggered or overlapping relation, as previously discussed, forming peripherally or circumferentially unobstructed outflow ports just as in Fig. 1. It should be observed, however, that in the case of Fig. 3, all the ports in the flow-distributing wall are outflow or discharge ports, the inlet being provided by the pipe 113. The outflow port between the inserts or baffles 117-118 is indicated at 119. At the bottom of the baffle 117 are the outflow ports 120 which may be slots, as shown. In place of these slots an unobstructed outflow port such as 119 may be provided in accordance with remarks made before. The outflow ports 120 discharge into the chamber 121 for withdrawal through the conduit 122. The discharge port 119 discharges into the chamber 123 for withdrawal through the conduit 124.

The upflow within the sump separator is again a streamcurrent flow, as previously described and as indicated in the flow lines in Fig. 3. The heaviest components of the underflow from the de-watering screens 104 and 110 are directed over the edge of the deflector 114 and gravitate downwardly for discharge through the ports 120 by way of the chamber 121 and conduit 122. Successively lighter components seek upwardly vertically successively disposed discharge levels for discharge from the apparatus. The lightest components, which may be coal fines, are discharged at the highest level. In Fig. 2, it is assumed that the material discharged from the four bottom levels is refuse, and in that case it is joined with the refuse coming from the de-watering screen 104. The coal fines discharged from the highest level may be joined with the clean coal from the de-watering screen 110. The products discharged from all of the levels of the sump may be refuse, and all of them are then disposed with the refuse. Alternatively, the two highest levels may contain valuable fines and both of them may be directed for intermixture and disposal with the clean coal. Clean water recovered from the various discharge and settling chambers, which may correspond to the chambers 26-30 and 66, 68 of the structure shown in Fig. 1, is directed by way of valve 101 and a valve-controlled conduit 125 for return to the separator shown in Fig. 1.

Some water is lost and discharged from the primary separator together with the clean coal and together with the refuse. The amount of water which is lost is replaced by makeup water

from the conduit 100. Water may, however, be sprayed on the de-watering screens to facilitate the handling of material, and the total water injected into the sump and clear water available from it, may exceed the amount lost in the primary separator. The excess water is made available for use by way of the valve-controlled outlet shown in Fig. 2. The makeup water, excess water and return water valves may be regulated by a simple constant level float control in the primary separator, as mentioned before.

The separator shown in Fig. 1, so far as described, is operated as an uprising current separator. In present-day separators of this general class, which usually furnish only two separated products, fines accumulate within an intermediate level of the liquid separating medium, remain therein, and change the characteristics of the uprising current separator into a heavy density separator, with consequent loss of valuable material, contamination of the desired discharged products, and need for constant supervision which increases labor costs. The same troubles also arise in the operation of orthodox heavy density separators, including those which use a so-called stable fluid separating medium. The density gradually increases beyond that which is desired for any given operation. Such alteration of the characteristics of the separator cannot occur in the present case, simply due to the fact that there is a constant exchange and withdrawal of liquid and material from vertically successively placed levels of the body of the liquid separating medium which prevents accumulation and retention of fines in any level thereof. The invention thus removes one of the prominent drawbacks of previous separators, which is particularly pronounced when it is attempted to use such separators for the treatment of raw material of relatively small particle size or material containing large amounts of fines.

It may be desired, however, to modify the operation of the new separator, withdrawing only two separated products, one at the bottom and one at the top level, and to use as a separating medium either water or a heavy density medium. Fines could accumulate in the liquid and could change the characteristics of the system, under such condition, as indicated in the foregoing paragraph. In order to avoid trouble in such operation, it is desirable to provide for control of the relative density of the separating medium so as to maintain it substantially constant. The circular suction pipes 70 and 73 within the settling chambers 66 and 68 are for this purpose provided at an intermediate or at a lower level, as indicated in dotted lines in Fig. 1, so as to withdraw and to circulate liquid containing heavy density particles back to the inlets of the separator. A similarly placed circular suction pipe may be provided at an intermediate level in the chamber 30 for withdrawing heavy density liquid from the port 18. The suction applied to the pipes in chambers 30, 66, 68 is such that only liquid is withdrawn containing substantially only those particles which tend to increase its specific density. The withdrawn material may then be circulated through a density control device shown diagrammatically in dotted lines in Fig. 1 and indicated by numeral 130, which device may be constructed and controlled generally along the lines disclosed in co-pending application Ser. No. 697,982. The settling and clarifying function of the chambers 30, 66 and 68 are in this case ignored, and heavy density liquid is

drawn directly from these chambers into the pipe 11. The settling and clarifying function of the discharge chambers 21—29 is, however, retained. The density control device 130 may also be provided in a by-pass conduit disposed in parallel with the pipe 11 and drawing only heavy density liquid from all or some of the chambers 66, 68, 30, for controlling, checking and correcting purposes, and for re-injection into the separator.

The accumulation of fines within the wetting and turbulence chamber formed by the feed conduit 47 is theoretically possible but practically will have no detrimental effect, if it arises, because, whether or not the dispersion, wetting and the required mobility are imparted to the particles in water or in a heavy density medium is substantially immaterial. All the solids of the raw material, including fines, ultimately work down from the wetting and turbulence chamber into the streamcurrent separating chamber. Bleeder conduits such as the one shown in Fig. 1 at 131 may, however, be provided. Several such bleeder conduits may be used and angularly spaced for symmetric downward discharge into the relatively low density and relatively quiescent top level of the streamcurrent chamber. Fines accumulating in the turbulence chamber, tending to change the liquid therein to a heavy density liquid, beyond a desired point, thus bleed automatically downwardly into the streamcurrent chamber, and the heavy density particles discharged by such bleeding are subjected to the streamcurrent flow and separation as previously discussed.

The separator may also be used as a classifier for separating materials of given specific gravities in accordance with the sizes of the particles thereof. For example, a material composed of particles of a substantially uniform specific gravity, but varying in size from 3" to 0", or any other suitable size range, may be fed into the machine, and the streamcurrent displacement may be adjusted so as to deliver the fines on top, successively larger, from pea to nut size particles at vertically downwardly successive levels, and to discharge the largest lump-sized particles at the bottom.

Structural modifications are likewise possible. For example, the discharge or outflow ports in the flow-distributing wall may be of varying width to provide a relatively narrow top discharge port for the fines, and downwardly progressively wider discharge ports for the discharge of successively larger particles. It is understood, of course, that the width of the ports exceeds in any case the size of the largest particles which are discharged therethrough. The relative amounts of fluid removed from each port are not affected by its width, being controlled by the operation of the pump and the relative setting of the corresponding valve in the streamcurrent circuit. The separator structure is shown to be circular and the flow-distributing wall of generally inverted cone shape. The structure may be made of angular configuration; for example, it may be square on top and the flow-distributing wall may be of the shape of an inverted pyramid.

It may be remarked, in conclusion, that the separator may be made for any practically desired ton-hour capacity and for treating materials other than coals and within size and specific gravity ranges other than mentioned in the foregoing description. Some of the features of the

invention will be found useful in apparatus and systems other than relating to the separation of materials, and particularly in basic processes and machinery such as noted in the previously mentioned patents. The invention is structurally as well as functionally versatile and adaptable, and presents new possibilities which will be apparent to those skilled in the art.

What is believed to be new and desired to have protected by Letters Patent is defined in the appended claims.

I claim:

1. A hydraulic separator comprising an upright tank, inlet means disposed centrally axially of said tank for injecting liquid thereinto radially outwardly in a plurality of levels thereof, means for withdrawing liquid centrally annularly upwardly from an upper stratum of the liquid body in said tank, means for feeding a stream of material particles centrally axially downwardly into the upper stratum of the liquid in the tank, and means for withdrawing adjusted amounts of liquid and material particles peripherally symmetrically from a plurality of vertically spaced levels of the liquid in said tank.
2. The structure and combination defined in claim 1, together with a tubular holder extending into the liquid in said tank downwardly centrally axially thereof for receiving the raw material particles for passage therethrough into the liquid body in said tank.
3. The structure and combination defined in claim 1, together with a tubular holder extending into the liquid in said tank downwardly centrally axially thereof for receiving the raw material particles for passage therethrough into the liquid body in said tank, and means for irrationally agitating the liquid in said holder for the threefold purpose of dispersing and wetting the raw material particles passing therethrough and of imparting mobility to such particles prior to feeding the particles into the liquid in said tank.

GEORGE A. AUER.
